UNITED STATES PATENT OFFICE

96,694

DESIGN FOR A BRUSH

Clyde A. Porter, Aurora, Ill., assignor to National
Brush Company, Aurora, Ill., a corporation of
Illinois

Application April 22, 1935, Serial No. 56,503

Term of patent 7 years

To all whom it may concern:

Be it known that I, Clyde A. Porter, a citizen of the United States, residing at Aurora, Illinois, post office address 460 Grand Avenue, Aurora, Illinois, have invented a new, original, and ornamental Design for a Brush, of which the following is a specification, reference being had to the accompanying drawing, forming part thereof.

Fig. 1 shows a perspective view of my new design for a brush.

Fig. 2 is a front elevation thereof.

Fig. 3 is a side elevation of my new design for a brush; and

Fig. 4 is a top plan view thereof.

Figs. 2, 3, and 4 are drawn on a slightly smaller scale than Fig. 1.

A dominant feature of the brush is the distinctive shape of its handle and bristle holding portions, both of which are of elongated shape, the bristle holding portion being generally octagonal, with two elongated sides, the sides of the bristle holding portion extending substantially vertically from its bottom, and its bottom lying in three different planes with two end planes sloping upwardly from the center plane.

I claim:

The ornamental design for a brush as shown and described.

CLYDE A. PORTER.
